FINGER RING SETTING OR SIMILAR ARTICLE

Joseph Weiss, Maplewood, N. J., assignor to Tessler & Weiss, Inc., Union, N. J., a corporation of New Jersey

Application November 25, 1955, Serial No. 39,049

Term of patent 14 years

(Cl. D45—10)

Fig. 1.

Fig. 2.

I claim:

The ornamental design for a finger ring setting or similar article, as shown.
